(57) **CLAIM**

The ornamental design for an insulating rail top bracket, as shown and described.

DESCRIPTION

FIG. 1 is a front perspective view of an insulating rail top bracket showing my new design;
FIG. 2 is rear perspective view thereof;
FIG. 3 is a front view thereof;
FIG. 4 is a rear view thereof;
FIG. 5 is a right side view thereof;
FIG. 6 is a left side view thereof;
FIG. 7 is bottom view thereof; and,
FIG. 8 is a top view thereof.
